UNITED STATES PATENT OFFICE

OSCAR J. LE BOEUF, OF GARY, INDIANA

CATCHER FOR ROLLING MILLS

Application filed October 27, 1928. Serial No. 315,485.

This invention relates to catchers for rolling mills and more particularly to a device for receiving bars from the rolls of a mill and returning these bars over the upper roll 5 to the front of the machine, so that they may be again fed through the rolls to complete the rolling operation.

An important object of the invention is to provide a novel mechanism which will receive the slab from the rest bars upon which it is discharged by the rolls, elevate the same and discharge the slab upon the upper roll at a point in advance of the center, so that the rotation of the roll will cause the slab 15 to be delivered to a point where a workman can return it to the rolls.

A further object of the invention is to provide a novel and improved lifting mechanism having associated therewith latching means by means of which the lifting mechanism is caused to tilt, so that in receiving the bars, the bars move inwardly thereon and are securely held and in discharging the bars, the bars are slid outwardly, so that they may 25 be readily discharged.

A still further object of the invention is to provide a novel and improved control mechanism for the latching mechanism above referred to.

These and other objects I attain by the construction shown in the accompanying drawings, wherein for the purpose of illustration is shown a preferred embodiment of my invention and wherein:—

Figure 1 is a side elevation partially in section showing a catcher for rolling mills constructed in accordance with my invention;

Figure 2 is a plan view thereof, parts being removed;

Figure 3 is an enlarged longitudinal sectional view through the catcher tongue;

Figure 4 is a side elevation of the latch showing the engagement with the tongue;

Figure 5 is a bottom plan view of the 45 tongue.

Referring now more particularly to the drawings, the numerals 10 and 11 designate the upper and lower rolls of a rolling machine and 12 spaced rest bars upon which the slab or bar 13 delivered from the rolls is discharged. In accordance with my invention, I dispose at the discharge side of the rolls and in spaced parallel relation thereto a shaft 14, which may be conveniently driven by a motor 15 at a relatively slow speed. This 50 shaft has secured thereto spaced spiders 16 having aligned pairs of arms 17 with each of which a tongue 18 is associated. The tongue 18 is of slightly less length than the distance between adjacent rest bars and is 55 in the form of an elongated body having its forward edge tapered, as at 19, and provided adjacent its opposite end edges with guides 20. Slidably in the guides 20 is a transversely extending shaft 21 and pivoted to the guides centrally thereof is a shaft 22 having a crank 23 to which the shaft 21 is linked in such manner that this shaft may slide from front to back of the tongue and from one side to another of the pivots or bearings of the 60 shaft 22. The ends of the shaft 21 are pivoted in the arm 17, and it will be obvious that when this shaft is disposed rearwardly upon the tongue with respect to the bearings 65 of the shaft 22, the outer end of the tongue 70 will tend to move downwardly by gravity, while, if the shaft is disposed at the outer end of its movement and beyond the bearings of the shaft 22, the rear end of the tongue will tend to move downwardly by gravity. The 75 rear end of the tongue has secured thereto a catch 24 disposed at one end thereof, for a purpose presently to appear.

Each arm has pivoted thereto a latch element 25 which is in the form of a bar 26 having a nose 27, which projects forwardly when the latch depends from the arm and which, at its junction with the bar, is provided with a cove 28 in its lower face, which is of a size sufficient to receive the latch pin 24 of the 80 85 90 95

associated tongue. Pivoted to the bar above the lower edge of this nose is a latch 29 which is adapted to obstruct the mouth of the cove 28 at times when the bar depends and during movement of this bar in a clockwise direction 5 from this depending position to a position where the bar is vertically directed and extends upwardly from the arm 17. A stop 30 carried by the latch and engaging the bar prevents the latch from overswinging its locking position and the weight of the latch is such that it may be displaced when the pin 24 engages therewith to permit this pin to enter the cove 28, after which the latch swings 10 to the cove-closing position and prevents the escape of the pin.

The latch is mounted upon a shaft 31, which extends through the arm and is provided at the outer face thereof with a pair of cranks 20 32 and 33. At the inner end of each arm is disposed a pivot having mounted thereon a substantially elliptical interrupted gear 34 to which is secured an eccentric pin 35 having a crank 36. The crank and pin are connected by links 37 with the cranks 32 and 33 of the shaft 31, so that when the elliptical gear is rotated, the shaft 31 will be rotated, causing the latch to rotate in a clockwise direction. 25

A shaft 38, which may be also driven from the motor through a cross shaft 39 with which the shaft 38 has chain and sprocket connections 40 and having chain and sprocket connections with the motor, as at 41, has at its 35 inner end a gear 42 aligned with the elliptical gears 34 and adapted to engage therewith during certain periods of the rotation of the shaft 14. Arcuate guides 43 are provided with which the free edges of the tongues 18 40 coact from a point where they are diametrically opposed to the rolls 10 to a point adjacent the rolls and on the downward 180° of their travel. These guides tilt the tongue 18 to provide for engagement of the latch bars therewith, as will hereinafter more fully appear. 45

In the operation of the device, assuming a given tongue to be at the limit of its movement which is diametrically opposed to the 50 rolls, the tongue is depending with the pivot shaft 21 disposed at the inner end thereof. The latch pin 24 which is disposed inwardly of the ends of the slides thus lies above the arm 17 with which the tongue is associated. 55 At this time, the associated latch bar depends from the arm 17 inwardly of the tongue 19 and will remain in this dependent position by gravity as this arm moves around through the sequence until it is actuated through its 60 gear 34. As the arm 17 referred to moves downwardly, the tongue 19 comes into engagement with the guide and by this guide is deflected, so that when the arm is substantially perpendicularly disposed and dependent, the tongue is practically horizontally 65

disposed. At this time, the latch 25 is positioned to swing past the pivot of the tongue and the latch pin thereof, so that it lies rearwardly of this latch pin and in a position to receive the same. 70

As the arm continues its movement, the tongue 19 comes into engagement with the bar 13. This causes the forward upward movement of the tongue to be arrested, with the result that this tongue is first forced downwardly so that its latch pin is engaged by the latch and then slightly rearwardly. At this time, the gear 42 engages the gear 34, causing practically a three-fourths revolution thereof while the arm is moving through approximately 40°. This movement causes the rear end of the tongue to be first drawn inwardly and downwardly, with the result that the bar 13 is withdrawn from the supports 12 and carried by the tongue. The withdrawal of the tongue is sufficient to cause it to clear the upper roll 10 while supporting the bar 13. As the arm reaches a position where the outer end of the tongue is above the upper end of the roll, the tongue is forced forwardly, with the result that the pivot of the tongue and the pivotal connection of this tongue with the arm are displaced in a manner permitting the forward end of the tongue to drop down, disengaging the tongue from the latch, the auxiliary latching member of which has at this time fallen away by gravity, so that a sudden sharp tilting movement takes place and the bar 13 is slid from the tongue onto the upper surface of the roll, by means of which it is returned to the front of the machine for handling by the attendants. 80

It will be obvious that the structure employed is capable of a considerable range of change and modification without in any manner departing from the spirit of the invention and I accordingly do not limit myself to such structure particularly illustrated and described except as hereinafter claimed. 85

I claim:—

1. In a catcher for a rolling mill and in combination with the rolls and the bar receiving rests of the mill, a rotatably mounted member, a tongue adapted to engage the bar upon the rests, means connecting the tongue to said member for rotation therewith and for pivotal and forward and rearward movements with respect thereto, means adapted on the engagement of the tongue with the bar to latch the tongue to said member so as to permit the tongue to carry the bar from the rests above the upper roll, and means adapted after the tongue is latched to shift it rearwardly with respect to said member so as to clear the upper roll and to thereafter shift it forwardly so as to cause it to overlie the upper roll and discharge the bar. 115
2. In a catcher for a rolling mill and in 120

2. In a catcher for a rolling mill and in 125

combination with the rolls and the bar receiving rests of the mill, a rotatably mounted member, a tongue adapted to engage the bar upon the rests, means connecting the tongue to said member for rotation therewith and for pivotal and forward and rearward movements with respect thereto, a latch movably connected to said member and adapted on the engagement of the tongue with the bar to hold the tongue so as to permit it to carry the bar from the rests above the upper roll, and means adapted to operate the latch so as to shift the tongue rearwardly to permit it to pass the upper roll and adapted thereafter to operate the latch to shift the tongue forwardly to cause it to overlie the upper roll and discharge the bar.

3. In a catcher for rolling mills and in combination with the rolls of a rolling mill and rest bars receiving a slab or bar from the rolls at the rear thereof, a rotating structure including pairs of arms each provided with a tongue adapted to engage a bar disposed upon the rest bars, said tongues being longitudinally shiftable upon the arms, a rotating latch associated with each arm and adapted to engage a latch pin carried by the tongue upon engagement of the tongue with the bar, and means for positively rotating said latch after its engagement with the tongue to thereby cause the tongue to first move inwardly to clear the upper roll and then outwardly to overlie the upper roll and position the bar for discharge thereover.

4. In a catcher for rolling mills and in combination with the rolls of a rolling mill and rest bars receiving a slab or bar from the rolls at the rear thereof, a rotating structure including pairs of arms each provided with a tongue adapted to engage a bar disposed upon the rest bars, said tongues being longitudinally shiftable upon the arms, a rotating latch associated with each arm and adapted to engage a latch pin carried by the tongue upon engagement of the tongue with the bar, and means for positively rotating said latch after its engagement with the tongue to thereby cause the tongue to first move inwardly to clear the upper roll and then outwardly to overlie the upper roll and position the bar for discharge thereover, said latch automatically releasing the tongue when the tongue is in the last named position to permit the outer end of the tongue to drop.

5. In a catcher for rolling mills and in combination with the rolls of a rolling mill and rest bars receiving a slab or bar from the rolls at the rear thereof, a rotating structure including pairs of arms each provided with a tongue adapted to engage a bar disposed upon the rest bars, each tongue having a longitudinally extending guide slot, pivots carried by each pair of arms and extending into the guide slot, a latch pin carried by the

inner end of each tongue, latch mechanism carried by each pair of arms adapted to engage said latch pin, and means for positively rotating the latch mechanism during a predetermined period of rotation of said structure.

6. In a catcher for rolling mills and in combination with the rolls of a rolling mill and rest bars receiving a slab or bar from the rolls at the rear thereof, a rotating structure including pairs of arms each provided with a tongue adapted to engage a bar disposed upon the rest bars, said tongues being longitudinally shiftable upon the arms, a rotating latch associated with each arm and adapted to engage a latch pin carried by the tongue upon engagement of the tongue with the bar, means for positively rotating said latch after its engagement with the tongue to thereby cause the tongue to first move inwardly to clear the upper roll and then outwardly to overlie the upper roll and position the bar for discharge thereover, comprising an elliptical gear link-connected with the latch and supported by the structure and a rotating gear with which said elliptical gear engages at a predetermined point in the rotation of said structure.

7. In a catcher for rolling mills and in combination with the rolls of a rolling mill and rest bars receiving a slab or bar from the rolls at the rear thereof, a rotating structure including pairs of arms each provided with a tongue adapted to engage a bar disposed upon the rest bars, said tongues being longitudinally shiftable upon the arms, a rotating latch associated with each arm and adapted to engage a latch pin carried by the tongue upon engagement of the tongue with the bar, means for positively rotating said latch after its engagement with the tongue to thereby cause the tongue to first move inwardly to clear the upper roll and then downwardly to overlie the upper roll and position the bar for discharge thereover comprising an elliptical gear link-connected with the latch and supported by the structure and a rotating gear with which said elliptical gear engages at a predetermined point in the rotation of said structure, said latch automatically releasing the tongue when the tongue is in the last named position to permit the outer end of the tongue to drop.

8. In a catcher for rolling mills and in combination with the rolls of a rolling mill and rest bars receiving a slab or bar from the rolls at the rear thereof, a rotating structure including pairs of arms each provided with a tongue adapted to engage a bar disposed upon the rest bars, each tongue having a longitudinally extending guide slot, pivots carried by each pair of arms and extending into the guide slot, a latch pin carried by the inner end of each tongue, latch mechanism carried by each pair of arms adapted to en-

gage said latch pin, means for positively rotating the latch mechanism during a predetermined period of rotation of said structure, comprising an elliptical gear link-connected with the latch and supported by the structure, and a rotating gear with which said elliptical gear engages at a predetermined point in the rotation of said structure.

10 In testimony whereof I hereunto affix my
signature.
